UNITED STATES PATENT OFFICE.

FRANCIS EDWARD BOWLES FRIPP, OF BROCKENHURST, ENGLAND, ASSIGNOR TO
COLIN HUNTLY GORDON, OF CHRISTCHURCH, NEW ZEALAND.

APPARATUS FOR CUTTING TAPERED ELLIPTICAL HOLES.

1,342,261.

Specification of Letters Patent.

Patented June 1, 1920.

Application filed December 31, 1918. Serial No. 269,168.

To all whom it may concern:

Be it known that I, FRANCIS EDWARD BOWLES FRIPP, a subject of the King of England, residing at Brockenhurst, Hampshire, 5 England, have invented certain new and useful Improvements in Apparatus for Cutting Tapered Elliptical Holes, of which the following is a specification.

This invention is for improvements in or 10 relating to apparatus for cutting tapered elliptical holes, and has for its main object to provide means whereby such holes can be quickly and accurately cut in maul-heads, such as are used by the Army for stake- 15 driving.

According to this invention, there is combined with a carrier for the maul-head or other part to be operated upon, a radius-rod fulcrumed at one end to permit of universal 20 movement, a templet operatively connected with the radius-rod to limit its movement, and guiding-means to prevent the radius-rod from rocking about an axis passing through the fulcrum point and the point of contact 25 with the templet.

Preferably the guiding-means to prevent rocking of the carrier takes the form of a long rod projecting from the carrier or a part secured thereto approximately radial to 30 an axis passing through the fulcrum point of the radius-rod and the center of the figure provided by the templet, and a support for that end of the rod remote from the carrier, which support is such as to permit of end- 35 wise movement of the rod and also swinging movement of the carrier end of the same.

The long rod may be hinged relatively to the carrier to permit of relative movement of the carrier and rod but not in the direction 40 in which the carrier would tend to rock about the point of contact with the templet.

The support for the projecting end of the long rod may be so situated at a point half-way between the limits of movement of the carrier in the direction in which rocking about the point of contact with the templet is to be prevented so that the slight tilt of 45 the carrier caused by the rod occurs half at the limit of its movement in one direction and half at the limit of its movement in the other direction.

In the accompanying drawings which illustrate one method of carrying out this invention:—

Figure 1 is a side elevation of the apparatus;

Fig. 2 is a plan of the same, and

Fig. 3 is a face view of the templet.

The same letters indicate the same parts 60 throughout the drawings.

The apparatus is built up on cross-slides supported by a table, the top slide 1 only being shown in the drawings. Secured to this slide is a bracket 2 conveniently made 65 of strip steel bent approximately into the form of a V and turned over at the angle of the V so that the flat face is brought to a horizontal position to support a fulcrum-pin 3. A similarly shaped radius-rod 4 extends horizontally from the fulcrum-pin 3 and then is bent down at right-angles and secured to a wooden carrier 5. The arms of the radius-rod 4 are secured to opposite sides of the carrier and they extend upward as at 4^b to provide bolts 4^c which receive a cross-bar 6 and tightening nuts 7.

The top of the carrier 5 is recessed as at 5^a to receive the maul-head 8 which is to be operated upon and the maul-head is held 80 firmly in place by the cross-bar 6 when this is forced down upon it by the handled nuts 7.

Secured to an inclined block 9 on the slide 1 is a templet 10. The templet has in it an 85 oval channel 10^a and the face of the templet in which the channel is formed is placed at right-angles to the axis indicated at X—X which passes through the fulcrum-point of the radius-rod 4 and through the central 90 point of the figure, that is, the oval channel 10^a, provided by the templet.

A pin 11 fast on the carrier and conveniently provided with a roller lies in the channel 10^a.

Secured to the carrier 5 is a metal strip 13 which extends around one side of the carrier and there provides an operating-handle 13^a, and also projects from the other side of the carrier as at 13^b to provide a bracket to 100 which a long (say 10 ft.) guide-rod 14 is connected. The guide-rod is connected to the bracket by a hinge 14^a whose axis is vertically situated.

The far end of the long-rod, that is the end 14^B which projects away from the carrier is supported on a roller 15 and passes loosely through a plate 16. The roller and plate are carried by any convenient fixed member and the arrangement allows the rod to have a universal movement and also an endwise movement. The roller could be dispensed with and the loosely-fitting plate 10 only employed, or two rollers superimposed could be employed provided the fit is loose enough to allow of a universal movement. The object of the second roller or of the plate 16 is merely to prevent the end of the 15 rod from being lifted.

The whole device is counterbalanced by a weight not shown in the drawings but which is connected by a cord 17 to a cross-bar 18 connecting the arms of the radius-rod 4.

20 The cutting-tool for operation upon the maul-head is shown at 19.

The operation of this device is as follows:—

The maul-head 8 to be operated upon is 25 dropped into the bed provided for it by the carrier 5 and the cross-bar 6, which is conveniently in the form of a spring bowed downward at the center, is then dropped over the bolts 4^C and pressed home by the 30 handled nuts 7. The cross-bar thus grips the maul firmly in place. The whole device is then moved by the cross slides up to the tool 19 which is shaped to cut at its end as well as at its sides. The maul-head is 35 pressed against the end of the cutter and by the handle 13^A it is made to move in the elliptical path provided by the templet 10. As the maul is thus fed forward and around in an elliptical path, the cutter enters the 40 maul and cuts a tapered elliptical hole, the degree of taper depending upon the length of the radius-rod 4.

Rocking of the arm about the point of contact of the templet-pin 11 with the templet 45 is prevented by the long guide-rod 14. The carrier can move relatively to the rod 14 by means of the hinge 14^A as it swings in a horizontal plane but the axis of the hinge being placed vertically prevents rocking of the 50 carrier 5 relatively to the rod 14. The carrier, however, swings with the rod in a vertical plane as it rises and falls by the engagement of the pin 11 with the templet 10 and the changes of path in this direction 55 due to the action of the guide-rod is equalized at the top and bottom of the elliptical channel 10^A by so situating the roller 15 that the center of the rod at the far end lies in the same horizontal plane as the axis X 60 which passes through the fulcrum of the radius-rod and the center of the elliptical figure provided by the templet.

The cutter is preferably formed of high-speed steel having the usual three or more

longitudinal blades. The end of the cutter 65 need not be provided with cutting edges and when this is so it will be necessary to provide a starting hole in the maul-head so that the cutter can be entered to bring the longitudinal blades into operation.

Obviously the radius-arm may be adjustable in length to allow for different tapers and the bracket 2 be correspondingly provided with adjusting means.

What I claim as my invention and desire 75 to secure by Letters Patent is:—

1. In apparatus for cutting tapered elliptical holes, the combination with a carrier for the maul-head or other part in which the hole is to be cut, of a radius-rod fulcrumed 80 at one end in such manner as to permit of universal movement, a templet operatively connected with the radius-rod to limit its movement, and guiding-means to prevent the radius-rod from rocking about an axis 85 passing through the fulcrum-point and the point of contact with the templet.

2. Apparatus for cutting tapered elliptical holes according to claiming-clause No. 1 wherein the guiding-means to prevent 90 rocking of the carrier takes the form of a long rod projecting from the carrier or a part secured thereto approximately radial to an axis passing through the fulcrum point of the radius-rod and the center of the 95 figure provided by the templet, and a support for that end of the rod remote from the carrier which support is such as to permit of endwise movement of the rod and also swinging movement of the carrier end 100 of the same substantially as described.

3. Apparatus for cutting tapered elliptical holes according to claiming-clause No. 2 wherein the long rod constituting the 105 guide to prevent rocking is hinged at the carrier end to permit of relative movement between the rod and carrier but not in the direction in which the carrier tends to rock about the point of contact with the templet.

4. Apparatus for cutting tapered elliptical holes according to claiming-clause No. 1 wherein the templet is situated away from the operating position of the tool (for example near the bottom of the carrier) and has that face whose periphery provides the 115 working edge at right-angles to an axis passing through the fulcrum point of the radius-rod and through the center of the finger provided by the templet substantially as described.

5. Apparatus for cutting tapered elliptical holes according to claiming-clause No. 2 wherein the support for the projecting end of the long rod is situated at a point half-way between the limits of movement of the 125 carrier in the direction in which rocking about the point of contact with the templet is to be prevented so that the slight tilt of

the carrier caused by the rod occurs half at the limit of its movement in one direction and half at the limit of its movement in the other direction.

- 5 6. Apparatus for cutting tapered elliptical holes according to claiming-clause No. 1 wherein the carrier with a supporting

bracket for the fulcrum end of the radius-rod is secured to a sliding table to which the templet may also be secured, substantially 10 as described.

In testimony whereof I affix my signature.

FRANCIS EDWARD BOWLES FRIPP.
